US00D783856S

(12) **United States Design Patent** (10) Patent No.: **US D783,856 S**
 Super et al. (45) Date of Patent: **** Apr. 11, 2017**

(54) **CORNER PROTECTOR FOR INSTRUMENT STERILIZATION TRAY**

(71) Applicant: **Summit Medical, Inc.**, St. Paul, MN (US)

(72) Inventors: **Marcus Felipe Super**, Minnetonka, MN (US); **Daniel Broberg**, Minnetonka, MN (US); **Kevin D. McIntosh**, Brooklyn Park, MN (US)

(73) Assignee: **Summit Medical, Inc.**, St. Paul, MN (US)

(**) Term: **14 Years**

(21) Appl. No.: **29/497,138**

(22) Filed: **Jul. 21, 2014**

(51) LOC (10) Cl. **24-02**

(52) U.S. Cl.

USPC **D24/227**

(57) **CLAIM**

The ornamental design for a corner protector for instrument sterilization tray, as shown and described.

DESCRIPTION

FIG. 1 is a perspective view thereof;

FIG. 2 is a side view thereof, as taken from the left side of FIG. 1;

FIG. 3 is a side view thereof; as taken from the right side of FIG. 1;

FIG. 4 is a front view thereof;

FIG. 5 is a back view thereof;

FIG. 6 is a top view thereof; and,

FIG. 7 is a bottom view thereof.
